UNITED STATES PATENT OFFICE.

GEORGE W. HUNT, OF BALTIMORE, MARYLAND.

LOAD-TIGHTENING LOW-TENSION BOLT RAIL JOINT.

Application filed September 30, 1927. Serial No. 222,987.

The invention relates to new and useful improvements in rail joints for road beds for rolling stock.

An object of the invention is to provide a rail joint having splice bars joining the ends of the rails, which joint is so constructed as to force the splice bars into contact with the rails for maintaining a tight joint by the wheel loads on the rails.

10 A further object of the invention is to provide a rail joint of the above character wherein the wear of the parts is taken up through the action of the wheel loads on the rails.

15 A further object of the invention is to provide a rail joint including splice bars and a base plate, wherein the wheel loads are carried solely by the base plate through the splice bars, and the parts are so constructed that the wheel loads will hold the joint tight, 20 partially freeing the bolts connecting the splice bars from strain under the loads, and also operate to compensate for the wear of the parts.

25 These and other objects will in part be obvious and will in part be hereinafter more fully disclosed.

In the drawings which show by way of illustration one embodiment of the invention—

30 Figure 1 is a view showing my improved rail joint in end view, and one of the rails as sectioned;

Fig. 2 is a side view of the joint.

The invention is directed broadly to a rail joint for joining the ends of rails on a road bed for rolling stock. The rail joint includes 35 three essential parts, two splice bars and a supporting base plate. The splice bars are similar in construction, and are shaped and proportioned so as to engage the rail directly beneath the tread portion thereof and the base flange of the rail, but so that said splice bars are normally free from contact with the web. The base plate is provided 40 with spaced risers, the inner faces of which are inclined to the vertical. Each splice bar has a projecting base portion, the outer face of which is inclined to correspond to the inclination of the inner face of the riser. The 45 risers are so positioned on the base plate that when the risers are in proper relation to the rail, the inclined faces of the base portion of the splice bars will engage the inclined inner faces of the risers. Normally, the upper face 50 of the projecting base portion of the splice bar is above the upper face of the riser. The

rail is normally free from the base plate and spaced above it, and supported entirely by the splice bars through their engagement with the base plate. Bolts are passed through the 60 splice bars for holding the same from slipping out of engagement with the rail when the rail is released from its load. Bolts are likewise provided for preventing the splice bars from slipping out of engagement with 65 the base plate when the load is released. The bolts, however, are not depended solely upon to maintain a tight joint, neither are they under full strain when the wheel loads pass over the ends of the rails connected by my improved rail joint. The wheel load on the rail is supported by the splice bars, and the splice bars in turn are supported by the base plate. These inclined faces tend to force the 70 splice bars toward the rail web, and thus it is 75 that the load will hold the splice bars in tight gripping contact with the rail. Any wear of the parts will be taken up by the load and absorbed by the spring washers.

Referring in detail to the drawings, my improved rail joint includes a base plate 1, splice bars 2, 2, bolts 3, 3 for joining the splice bars and holding the splice bars in place relative to the rail ends 4 and 5, and bolts 6, 6 which 80 secure the splice bars to the base.

85 Each base plate is provided with two risers 8 and 9. These risers are on opposite sides of the rail joint. The inner face of each riser is inclined as indicated at 10. The splice bars are similar in construction, and each splice 90 bar includes a bearing portion 11 which is normally adapted to engage the under face of the tread of the rails. The splice bars are also provided with bearing surfaces 12 which engage the base flanges 13 of the rails. Normally, neither splice bar engages the web 14 of the rail, for reasons which will be stated. Each splice bar has an outwardly projecting 95 supporting base or arm 15. The outer face is inclined as indicated at 16. The inclination 100 of this face of the splice bar is substantially the same as the inclination of the inner faces of the risers. It will be noted that the geometric axial plane of the projecting arm 15 is substantially horizontal and it is also disposed below a perpendicular to the inclined face of the riser at the line where said plane intersects the same. By this construction of the splice bar a slight spring action 105 is assured to the wheel load, thus mitigating 110 the effect of impact or shock.

The splice bars are provided with two holes

for bolts and only two bolts are necessary for joining the splice bars to the rail ends. These bolts pass through holes which are drilled very high in the web of the rail ends. Spring washers are used in conjunction with these bolts. There are only two hold-down bolts, one on each side of the rail joint, and spring washers are used with these bolts.

The wheel loads on the rail ends are supported entirely by the splice bars, and are transmitted through the splice bars to the base plate. The inclined faces of the risers on the base plate will force the lower part of the splice bars inward, and this will cause the splice bars to make tight contact with the rail and the base plate. The bolts 3, 3 therefore, are mainly for the purpose to prevent the splice bars from slipping out of place relative to the rails when the wheel loads are released. For this reason, the number of bolts used in joining the splice bars is reduced to a minimum. The holes being placed high through the web of the rail, better perform their function of preventing the upper ends of the splice bars from slipping out of proper relation to the rail. The force of the load on the rail ends through the splice bars will tend to move the splice bars downward against the base plate, as the rail is supported free of the base plate and solely by the splice bars, as noted above. The upper face of the base portion of the splice bar is normally above the upper face of the riser, so that as the parts wear, and the splice bars move further down along the inclined surface of the riser, the hold-down bolts may be tightened. These hold-down bolts do not carry the load, but function mainly to prevent the lower projecting ends of the splice bars from becoming displaced relative to the risers when the load is released. Inasmuch as the splice bars are bolted to the rails and the hold-down bolts pass through portions of the splice bars, and the base plates, and the base plates are also spiked to the ties, said hold-down bolts will serve to prevent rail creeping. Only two hold-down bolts are necessary. The inclination of the inner faces of the risers and the outer faces of the splice bars may be varied. It is essential, however, that they shall be so positioned as to produce a wedging action which forces the splice bars against the rail.

It will be noted from the above that my improved rail joint is maintained tight through the wheel loads on the ends of the rails, and therefore, the joint is constantly kept tight, taking up any wear as it occurs, and preventing lost motion in the joint, which of course, accelerates the wear. It will also be noted that my improved joint provides maximum rigidity under the load, when most needed, and relaxes when the load is released, and this will give a greater latitude for proper expansion and contraction.

It is obvious that changes in the details of construction and the proportion of the parts may be made without departing from the spirit of the invention as set forth in the appended claims.

Having thus described the invention, what I claim as new and desire to secure by Letters-Patent, is—

1. A rail joint including splice bars joining the ends of the rails and a base plate joining and supporting the splice bars, said splice bars each having a bearing surface adapted to engage the under face of the tread of the rail and a bearing face adapted to engage the base flange of the rail, said base plate having risers and said splice bars having projecting portions adapted to engage the risers whereby the rail is supported solely by the splice bars and risers, means for securing the splice bars together and to the rail, said projecting portions of the splice bars being so constructed and proportioned that the geometric axial plane of said projecting portions is substantially horizontal and disposed below a plane at right angles to the face of the riser at the line where said geometric plane intersects the same.

2. A rail joint including splice bars joining the ends of the rails and a base plate joining and supporting the splice bars, said splice bars each having a bearing surface adapted to engage the under face of the tread of the rails and a bearing face adapted to engage the base flange of the rail, said base plate having risers and said splice bars having projecting portions adapted to engage the risers whereby said rail is supported solely by the splice bars and risers, the contact faces between the splice bars and the risers being inclined upwardly and outwardly so that a plane perpendicular to the face of the riser midway between the vertical extremes of the bearing face of the riser intersects the web of the rail on a line intermediate the bearing surfaces of the splice bar on the rail.

3. A rail joint including splice bars joining the ends of the rails and a base plate joining and supporting the splice bars, said splice bars each having a bearing surface adapted to engage the under face of the tread of the rail, and a bearing face adapted to engage the base flange of the rail, said base plate having risers and said splice bars having projecting portions adapted to engage the risers whereby said rail is supported solely by the splice bars and the risers, bolts for joining the splice bars for maintaining the same in contact with the rail, and hold-down bolts for joining the splice bars to the base plate for holding the same in position relative thereto.

4. A rail joint including splice bars joining the ends of the rails and a base plate joining and supporting the splice bars, said splice bars each having a bearing surface adapted to engage the under face of the tread of the rail,

and a bearing face adapted to engage the base flange of the rail, said base plate having risers and said splice bars having projecting portions adapted to engage the risers whereby 5 said rail is supported solely by the splice bars and the risers, bolts for joining the splice bars for maintaining the same in contact with the rail, and hold-down bolts for joining the splice bars to the base plate for holding the 10 same in position relative thereto, the contact faces between the splice bars and the risers being inclined upwardly and outwardly, whereby the wheel load on the ends of the rail will tighten said rail joint.

15 5. A rail joint including splice bars joining the ends of the rails and a base plate joining and supporting the splice bars, said splice bars each having a bearing surface adapted to engage the under face of the tread of the 20 rail and a bearing face extending throughout the length of the bar adapted to engage the

base flange of the rail, said base plate having risers provided with bearing faces substantially parallel with the longitudinal axis of the rail, said splice bars including projecting 25 portions disposed at the lower extremity thereof and adapted to engage the bearing faces on the risers whereby the rail is supported solely by the splice bars and risers, 30 the contacting faces between the splice bars and the risers being inclined upwardly and outwardly, said risers being spaced from the web of the rail and having the lower ends of their inclined portions spaced above the lower ends of the inclined portions on the base plate whereby the wheel load on the end of the rail will tighten said rail joint, and means 35 for retaining said splice bars in place relative to the rail and the base plate.

In testimony whereof, I affix my signature.

GEORGE W. HUNT.
